UNITED STATES PATENT OFFICE.

JOHN O. JONES, OF MITCHELL, SOUTH DAKOTA.

VALVE-GEAR.

1,371,424.

Specification of Letters Patent. Patented Mar. 15, 1921.

Application filed January 23, 1920. Serial No. 353,408.

To all whom it may concern:

Be it known that I, JOHN O. JONES, a citizen of the United States, residing at Mitchell, in the county of Davison and State 5 of South Dakota, have invented certain new and useful Improvements in Valve-Gears, of which the following is a specification.

This invention relates to valve gears for engines, and more particularly to valve 10 mechanism for locomotives, and especially to that type of locomotives equipped with either the Baker or Walschaert valve gear both well known valve mechanisms.

Applicant's invention however may be 15 applied to any type of locomotive designed for valve gearing to be carried outside the frames, but as disclosed in the accompanying drawings the invention may be termed an attachment in that it may be most easily 20 applied to an engine equipped with a Walschaert motion of the design shown, which latter is in extensive use at the present time.

An object of the invention is to provide a valve gear wherein the valve lead varies 25 as the travel of the valve; or in other words wherein the lead varies as the reverse lever is notched up in the direction of the central notch, both in forward and backward motion.

30 As the lap is constant with all locomotive valve gears and as the lead is constant in the Walschaert gear, but one fixed lead is available from the time the engineer drops the reverse lever into the full forward notch until 35 he is running under the shortest cut-off of which the engine is capable. To work a high speed locomotive economically under a pressure of say two hundred pounds or more with a super-heating equipment it is essential 40 to cut off at a point somewhere between one quarter and one third stroke, and as it is desirable to have a liberal valve lead when so running so as to exhaust rapidly enough, many locomotives of this type are 45 designed with a constant lead ranging anywhere from three sixteenths to five sixteenths of an inch. As long as the engine is running at high speed such leads effects economical working and boost the engineers fuel record. But with the reverse lever in 50 the region of the full forward notch, or in other words, when "pulling out" with the full inertia of the train to overcome, and no momentum as an assisting factor, and 55 cutting off at about three fourths stroke a lead such as a quarter inch serves, not as a

cushion to effect a gentle reverse of the piston, but as a staggering resistance to the latter in the form of a back pressure, thereby rendering the working of 60 the engine heavy or what is sometimes called "loggy". Thus in a valve gear with a constant lead the economy effected during high speed is offset by waste encountered at low speed. It is the object of the present 65 invention to provide a valve gear wherein the travel of the valve relative only to its lap and lead is derived from the travel of the cross head, but which is provided with means for so modifying the motion transmitted to 70 the valve as to result in gradually increasing the lead as the time of cut-off is reduced. This prevents excessive back pressure since the minimum lead may be made very small (such as a thirty second or one sixteenth of 75 an inch) when starting a heavy train, and increase to three eighths of an inch at the minimum cut-off.

A further object of the invention is to provide a valve gear equipped with means 80 whereby the valve is momentarily delayed in its movement to hold the port open just after the piston starts its stroke.

To this end the invention consists in the construction, combination and arrangement 85 of parts hereinafter described and claimed. In the accompanying drawings forming part of the specification:

Figure 1 is a side elevation of a portion of a locomotive equipped with a much used 90 type of Walschaert valve gear the cylinder and valve chest being shown semi-diagrammatically in cross section, the short dark lines at the top of the figure outlining applicant's invention as an attachment. 95

Fig. 2 is a side elevation of the invention illustrating its application to a locomotive the crank being on back center.

Fig. 3 is a perspective view of the invention. 100

Figs. 4 and 5 are diagrams showing the crank on back center and lower quarter respectively.

Fig. 6 is a perspective view of the link partly broken away, the part broken away 105 being shown immediately to the left thereof.

Fig. 7 is a perspective view of the link end of the radius rod.

Fig. 8 is a perspective view of the upper end of the lap and lead lever. 110

Fig. 9 is a perspective view of the valve rod support.

Fig. 10 is a perspective view of one of the slide blocks of the combination lever, and

Fig. 11 is a diagram illustrating a phase of the valve movement.

Referring to Fig. 1 of the drawings, the parts of the Walschaert gear are as follows: A is the cross head, B the main connecting rod, C the main crank pin, D the eccentric crank, E the eccentric rod, F the link, G the radius rod, H the radius rod hanger, I the lifting arm, J the lifting shaft or rock shaft, K the lifting arm, L the reach rod, M the cross head arm, N the lap and lead lever connector, O the lap and lead lever, P the valve stem, Q the valve stem guide, R the radius rod guide and S the link foot.

In addition to these T represents the valve, U the cylinder, V the piston and its rod and W the cross head guide bars. In the application of the invention of the design shown in the drawings, the parts T, H, L, I, J, G, Q, O and R are removed. Extending from the top of the vertical member X of the frame to the top Z of the steam chest and disposed in the vertical plane in which move the valve rod and piston rod and arranged parallel to said rods and located directly above the cross head guide bars and a distance above the level of said steam chest top, is the slide way A'. The slide way is formed by housings 1 and 2 suitably secured respectively to the member X and the steam chest, the two housings being joined together by a pair of spaced guide bars 3 one above the other. While the slideway A' is shown supported on the steam chest cover Z and the member X, it is to be understood that it may be supported in any suitable manner, as, for example directly on, what is commonly termed the main frame which carries the boiler, not shown, and is indicated in dotted lines in Figs. 1 and 2, the three drivers being indicated in fine solid lines. The cylinder with its steam chest, the cross head guides and the member X are all supported on the main frame the mode of connection therewith not being shown and form collectively the adjacent supporting structure for the valve rod and the crosshead. Slidably mounted in said slide way is the cam block 5 having a uniformly curved or circular cam slot 6 of uniform width cut through the side thereof; the concavity of the slot being directed downwardly. Directly beneath the slide way A' and supported by means of stands 4 on the cross head guide bar and arranged parallel with the valve rod P is the valve rod guide bar 7 which slidably fits the opening 8 of the valve rod support 9. This support is provided with oppositely disposed laterally extending threaded studs 10 disposed perpendicular to the opening 8, and rotatably fitting the opening 11 of the slide 12. The latter is formed with a pair

of parallel channels 13, one on either side of the opening 11 said channels being longitudinally in a plane perpendicular to the longitudinal axis of said opening. The blocks 12, of which there are two, one for each of the studs 10 whereon they are held by means of the nuts 14, function as a sliding fulcrum for the lap and lead lever B' which may be described as follows. The lever comprises a downwardly extending wide flat long arm portion 15 and two oppositely disposed spaced upwardly extending short arms 16, one thereof alining with said long arm and the other being offset, the two arms forming a comparatively large bifurcation adapted to movably receive widthwise the valve rod support 9. Cut through the flat sides of the short arms 16 are the oppositely disposed elongated rectangular openings 17 adapted to slidably receive the portion 18 of the blocks 12 the channels 13 slidably receiving the long side walls of the openings 17. A pivot 19 is supported in said short arms and spans said bifurcation above the openings 17, and a pivotal connection 20 at the extreme lower end of the long arm 15 connects the latter with the connector link N, which latter is pivotally connected at 22 with the cross head arm M. The pivots 10-19-20 and 22 are all axially parallel and disposed horizontally at right angles to the path of travel of the piston. Likewise are the pivot pins 23 to 32 inclusive to be hereinafter specifically described. The pin 24 extends through the cam slot 6 of the cam block and pivotally supports, one on either side of the latter, a comparatively short downwardly extending connector lever 33 or floating lever, the lower end thereof being pivotally mounted on the pin 19 within the bifurcation of the lap and lead lever B'. Fixed one on either end of the pin 24 and extending horizontally to the stand 2 on the steam chest are the steady links 34, the opposite respective ends thereof being fixed on opposite ends of the pin 25 which latter is rotatably supported in said stand 2 as best shown in Fig. 2 the steady links are disposed horizontally when the lever 33 is positioned 110 radial or perpendicular to the curvature of the cam slot, the curvature of the latter being symmetrical about a vertical line bisecting the cam slot midway between its ends. Thus the lever 33 will move bodily downwardly the same degree on either side of said bisecting line when the cam block is slid. Pivotally connected by means of the pin 26 to the cam block is the rearwardly extending tie rod 35, having pivotal connection 31 125 with the comparatively short vertical arm 36 fixed on the rock shaft 37 the latter being supported horizontally on the engine frame and at right angles to the line of travel. The crank arm 38 is also fixed on the rockshaft 130

and has pivotal connection 32 with the reach rod 39 leading to the cab, from whence the engineer actuates the rockshaft. Fixed on the outer end of the rockshaft is the lifting arm 40 having pivotal connection 29 with the lifting link 41, the latter having pivotal connection 28 with the radius rod 42. The radius rod is formed (Fig. 7) with a deep bifurcation 43 having a transverse pivot 5 pin 44 projecting therethrough. The opposite end of the radius rod has pivotal connection 23 with the levers 33, said pivot constituting a fulcrum whereby when the radius rod is moved longitudinally the lever 33 will 10 carry the lead lever B' with it and thereby move the valve T. It will be noted that as the levers 33 are swung upon their pivots 24, the lead lever is moved bodily the link N yielding vertically and the blocks 12 sliding in the openings 17. The radius rod has the usual slide block connection with the link C' (Fig. 6). The link shown comprises a circular segment open at its curved edges, its concave edge being directed forwardly. Midway between its ends it is provided on opposite sides with a transversely disposed trunnion pin 27 the latter being journaled respectively in the spaced lugs 45 forming part of the housing 1. The housing 1 extends rearwardly beyond the cross-head guides so as to render the radius rod as long as possible, the latter straddling loosely with its bifurcation 43 the central rib 46 of the link. The rib 46 is formed 20 with a longitudinally centrally disposed slot 47, wherein works slidably the block 48 having a bore 49 axially capable of alinement with the trunnions 27, the pin 44 being journaled in said bore. Thus, when the link is caused to be rocked about its trunnions and the pivot 44 is coincident with the latter as shown in Fig. 2 of the drawings no motion is transmitted to the lever 33 suspended from the cam block 5, the valve gear 25 operating precisely as does the Walschaert shown in Fig. 1. The ratio however of the distance between the pivots 10 and 19, to the distance between the pivots 10 and 20 is greater than the ratio between the corresponding distances in the Walschaert valve gear because (as stated in the foregoing) the lead in the latter is constant, or, in other words the throw of the short arm of the lap and lead lever is designed to equal twice the 30 lap plus twice the lead, and since the lead is limited to about one quarter inch for reasons explained in the foregoing, the ratio must be smaller. When positioned as shown in Fig. 2 the throw of the short arm 35 of the lever B' is maximum, which may be designed to yield a lead of three eighths of an inch or more as desired, the pin 24 it being noted resting on the highest part of the cam slot 6.

65 Referring to Figs. 4 and 5 of the draw-

ings, the reach rod 39 is represented diagrammatically as being connected with the reverse lever indicated by the numeral 50, and working in connection with a notched rack indicated by the numeral 51.

70

In Fig. 4, the reverse lever is assumed to be in the first notch (the notches not being indicated) the cam block having cammed down bodily the lap and lead lever B' whereby the length of the short arm thereof (or 75 that part above the fulcrum 10) has been reduced an amount indicated at 52. Obviously the long arm 15 has thereby been proportionally lengthened. Thus, in Figs. 4 and 5 the throw of the short arm is minimum, Fig. 5 showing the reverse lever as being in the rearmost notch. The minimum throw may be so proportioned as to yield a sixteenth of an inch or less lead which would be ample for cushion purposes, that 80 being the main object of any lead when the reverse lever is in a far forward notch. The lead, therefore, gradually increases from about one sixteenth to maximum as the reverse lever is "notched up" and the pin 24 85 thereby simultaneously cammed up in the cam slot.

90

In Fig. 4, the crank is on back center, the port being open to the extent of the maximum lead alone, but the eccentric being approximately on lower quarter, (its most active link moving position), will rapidly move the valve so as to fully open the port through a fraction of the next quarter. The movement of the valve at this point is modified so as to momentarily but not abruptly reduce its rate of speed, the port being thereby held open for a longer period of time and then rapidly closed by the combined action of the link and lead lever. This action is illustrated in Fig. 11 wherein the eccentric is approximately on lower back 95 eighth and the crank on upper back eighth the reverse lever being assumed to be in full forward notch. The modified motion is due 100 to the oppositely disposed fulcrumed levers 33 and B', which (Fig. 11) when becoming longitudinally alined partially neutralize each other's valve moving action in that their short arms joined by the pivot 19 are at this 105 time traveling in the same direction (see arrows) thereby rendering the pivot 10 almost stationary. So soon however as the crank reaches upper center both the crank and eccentric travel forward to rapidly close 110 the port.

115

The best results are to be obtained by making the rods or links 34 and the radius rod E as long as possible so as to reduce the arcs described by their respective adjacent outer 125 ends.

While applicant's radius rod is somewhat out of alinement with the valve rod the lever 33 forms a strut the pin 24 being approximately in the center of the cam slot (where 130

there can be no slipping) when the engine is going at high speed. As a drop of one half inch of the lever 33 is adequate to effect a satisfactory change of lead, the cam slot 5 may be of large radius so that the slipping or lost motion is almost negligible.

While applicant's valve gear is shown in connection with an internal-admission valve it is to be understood that the principle underlying applicant's invention may 10 be applied in connection with external-admission valves by simply reversing the pivots 10 and 23, that is, connecting the radius rod with the slideable pivot 10 and the valve 15 rod with the pivot 23 the lead thereby being rendered variable as in the construction shown.

I claim:

1. In a valve gear for locomotives the 20 combination with a valve rod, crosshead, main rod, main crank pin, eccentric on said crank pin, the reciprocatory link actuated by said eccentric, and the adjacent structure supporting said valve rod and crosshead, of 25 a lap and lead lever operatively connected with the crosshead and having slideable pivotal connection with the valve rod so as to reciprocate the latter when actuated, an upwardly extending lever arm pivotally connected to said lap and lead lever at a position 30 above said slideable pivotal connection, vertical yieldable pivotal link connections pivotally connected with the top of said lever arm extending approximately horizontally 35 away from the latter to a position on said structure to be pivotally mounted thereat whereby to hold the top of said lever arm so as to render the latter movable bodily vertically and swingable laterally, a radius 40 rod pivotally connected to said lever arm at a position between the lap and lead lever connection and the yieldable connections of the latter, said radius rod having slideable pivotal connection with said reciprocatory 45 link so as to be reciprocated thereby when actuated, and hand operable controlling mechanism supported on said adjacent structure operatively connected with said lever arm and said radius rod for bodily moving 50 both, said controlling mechanism including a slideable cam block engaging said lever arm to bodily raise and lower the latter for the purpose set forth.

2. In a valve gear for locomotives the 55 combination with the reverse lever, the valve rod, crosshead, main rod, main crank pin, eccentric on said crank pin, the reciprocatory link actuated by said eccentric, and the adjacent structure supporting all of said 60 parts, of a fulcrumed lap and lead lever being movable relative to its fulcrum and operatively connected below its fulcrum with the crosshead, said fulcrum being fixed on the valve rod, mechanism operatively connected with the reverse lever for moving at 65

will said lap and lead lever relative to its fulcrum, said mechanism including a cam block adapted to be slid when said mechanism is actuated, a swingable depending lever arm depending from and in engagement with said cam block to be raised and lowered thereby when the latter is actuated, and pivotally connected to said lap and lead lever at a position above its fulcrum, and a radius rod pivoted at its respective opposite ends to said lever arm and said link so as to be reciprocated by the latter when the latter is actuated, and means for actuating said radius arm, said radius arm being so connected with said lever arm as to bring the latter into longitudinal alignment for a period of time with the lap and lead lever during the valve moving action of the latter for the purpose set forth.

3. A valve gear for locomotives comprising 85 a lap and lead lever having pivotal link connection at its lower end with the crosshead to move therewith, a swingable lever arm pivotally connected at its lower end with said lap and lead lever, vertically 90 yieldable link connections for said lever arm extending to the adjacent structure of the locomotive and pivoted thereon so as to render said arm movable bodily vertically and swingable laterally, an oscillatory 95 curved link, a radius rod slidably pivoted thereon to be reciprocated thereby when actuated and pivotally connected at its forward end to said lever arm at a position intermediate the ends thereof, means for moving said radius rod on said link to move the latter when oscillated, pivot means fixed on the valve rod, guiding means therefor, and slideable pivot means on the lap and lead lever near the upper end thereof to cooperate with said pivot means to reciprocate the valve rod when the lap and lead lever is moved, and lever mechanism including a cam operatively connected with said radius rod moving means and operating 105 concurrently therewith for simultaneously moving said lever arm bodily and causing it to be swung whereby to modify the movement of the lap and lead lever for the purpose set forth.

4. In a locomotive valve gear of the Walschaert type the combination with the frame, the crosshead arm, the link, the radius rod therefor, and the shifting mechanism for the latter, of a lap and lead lever 120 extending upwardly beyond the valve rod and having a vertically yieldable connection at its lower end with the crosshead arm, mechanism connected with said shifting mechanism and including a swingable and vertically movable lever arm pivotally connected intermediate its ends with the radius rod and at its lower end with the top of said lap and lead lever for moving the latter bodily vertically at will, said mechanism 125 130

including a horizontally slideable cam, engaging said swingable lever arm to raise and lower the latter when said mechanism is actuated, pivot devices for the lap and lead lever slideable on the frame and moving with the piston, and upwardly slideable means on the lap and lead lever to rotatably engage said pivot devices whereby the latter may be free to be moved by the combined horizontal and vertical action of said lever arm when said shifting mechanism is actuated.

5. In a locomotive valve gear of the Walschaert type, a slideable pivotal fulcrum connection connecting the combination lever with the valve rod, a depending swingable lever arm yieldably mounted at its upper end so as to be capable of moving bodily vertically and swing horizontally and located above the combination lever and

pivottally connected with the latter above 20 said slideable connection, said lever arm being pivotally connected with the radius rod intermediate its ends so as to be swung thereby, whereby its pivotal connection with the combination lever is moved relative to 25 said fulcrum connection to change the valve moving action of said lap and lead lever when the locomotive is moving, and means for simultaneously moving at will said depending lever arm and the radius rod for 30 the purpose set forth.

In testimony whereof I affix my signature in presence of two witnesses.

JOHN O. JONES.
